ELECTRIC DRY SHAVER

Alfred H. Sorensen, Detroit, Mich.

Application June 20, 1938, Serial No. 214,620

5 Claims.

(Cl. 30—43)

This invention relates to improvements in razors, particularly razors of the electric dry shaver type.

Heretofore, razors of the dry shaver type have employed stationary skin-engaging plates, variously termed shear plates, combing plates and so forth. These plates have been slotted or perforated so as to guide hairs into engagement with either a reciprocating, revolving or oscillating cutter disposed on the reverse side of the stationary plate. Many different kinds of dry shavers have appeared on the market, achieving various degrees of commercial success, but it appears that one fundamental characteristic is common to all dry shavers thus far. In each, the hairs must project through at least one thickness of metal, however thin that may be, and be sheared off on the opposite side of that thickness of metal. It is true that some of the shear plates of the prior art have been extremely thin, so thin in fact as to necessitate internal bracing to prevent their collapse, but the fact remains that in each and every instance a thickness of metal is interposed between the skin surface and the cutter. It is manifest that most, if not all, of the dry shavers of the prior art must be pressed closely against the skin surface to actually raise the skin surrounding the base of the hair to a level nearer the cutter in order to closely cut the hair. This practice often results in numerous tiny abrasions and cuts, and yet, if the shaver is not pressed closely to the skin surface, a satisfactory shave is not generally obtained.

One object of this invention is to provide a skin-engaging head which will permit the cutting or shearing elements of an internal movable cutter to cut or shear hairs as close to the base as desired. A further object is to provide a dry shaver which need not be pressed closely against the skin in order that a close shave may be obtained. It is also an object of the invention to provide a dry shaver with which the closeness of the shave may be controlled by the operator by varying the angular positions in which the shaver is held in relation to the skin. The foremost object of this invention is the provision of a dry shaver in which the hairs come into direct contact with the cutter without passing through a thickness of metal and with which the chances of cutting or abrading the skin are substantially eliminated.

In the accompanying drawing Figure 1 is an end elevation showing a portion of the operating mechanism for an oscillating cutter. Figure 2 is an elevation taken from the right side of Figure 1 with parts thereof broken away to illustrate the cooperating action of the cutter and head. Figure 3 is an elevation similar to Figure 2 but with one half of the head removed. Figure 4 is an exploded view of the head and cutter. Figure 5 is a partial cross sectional view on line

5—5 of Figure 2 with cutter shown in neutral position. Figure 6 is similar to Figure 5 with the cutter shown in one cutting position. Figure 7 is a partial cross sectional view on line 7—7 of Figure 2 with cutter shown in opposite cutting position.

Referring now to the drawing, in which like references indicate like parts, the head portion of a dry shaver is shown in Figure 1. The invention relates primarily to the head and cutter portions and accordingly, the usual plastic or metallic case is indicated merely by broken lines as at 10. Suffice it to say that the case 10 contains a source of motive power such as a small electric motor, to be controlled by the usual hand switch (not shown).

Located in the opening of the case is a head indicated generally at 11. According to the preferred form of the invention, head 11 comprises two complementary portions 12 and 13 which, in order to make the description easier to follow shall hereinafter be called the left head and right head respectively. These head portions may be held in the case 10 by any well known means. In Figure 1 the head is illustrated as being held against the shoulders 14 of the case by means of knurled set-screws 15, which also serve to maintain the left head 12 and right head 13 in assembled relationship. In addition, one or more dowel pins 16 serve to locate and hold one head portion with respect to the other. In Figure 5, dowel 16 is shown as being press-fitted within right head 13 and slip-fitted within left head 12.

The head 11 is provided with a cylindrical opening, one half of the opening being in each head portion. This cylindrical opening is finely machined to provide a bearing for a rotating or oscillating cutter. The cutter comprises a tubular sleeve 17, which may be longitudinally split. The outer edges 19 of the split 18 are chamfered to remove the sharp edges. It will be understood that the sleeve 17, when unconfined, is of slightly larger diameter than the cylindrical opening 20 in the head. It follows that the sleeve 17 is compressed slightly when inserted between the head portions 12 and 13 and that this compression will cause the sleeve wall to be in firm contact with the wall of the cylindrical opening 20. This radially outward pressure is desirable to keep the cutter sleeve in firm engagement with the cylindrical opening, but is insufficient to cause excessive friction.

Cutter 17 is provided with a series of very narrow slots or kerfs 21 and 22, arranged alternately as shown in Figure 3 and extending inwardly of the cutter sleeve 17 nearly to the median line of the sleeve. The ends 23 of slots 21 and 22 are parallel and are very nearly normal to the walls of the sleeve 17.

The lower or skin engaging end of the head 11 may be rounded as indicated at 24 or may be

any other suitable shape and is preferably flattened off as at 25. Left head 12 is provided with a series of fine kerfs 26 extending horizontally as shown in the several figures. There kerfs 26 and the metal between each of them are approximately the width of an average hair. Right head 13 is likewise provided with a series of kerfs 27, disposed oppositely to kerfs 26 in left head 12. It will be understood that the metal between one of the kerfs 26 will be disposed opposite one of the kerfs 27. Kerfs 26 and 27 might be termed combing slots. Kerfs 21 and 22 in the cutter 17 and the thicknesses of metal between them are of the same width as the kerfs 26 and 27 in the head 11. Kerfs 21 are in alignment with kerfs 26 and kerfs 22 are in alignment with kerfs 27. The ends 23a of kerfs 21 coact with the sharp edges of the metal between kerfs 27 to shear hairs guided toward the shearing point by kerfs 26, and conversely ends 23b of kerfs 22 coact with the sharp edges of the metal between kerfs 26 to shear hairs guided toward the shearing point by kerfs 27. It will be seen in Figure 4, an exploded view, that by grinding or honing the bottom surfaces of the thicknesses of metal lying between kerfs 26 and 27 to form the flattened portion 25, the edges of these thicknesses of metal may be made extremely sharp, and that a hair brought into engagement with one of these sharp edges will be sheared by the cutter substantially at its base. Figure 6 shows the end 23a of one of the kerfs 21 immediately after it has been rotated past the edge of one of the thicknesses of metal between kerfs 27, and Figure 7 shows one of the alternate ends 23b immediately after it has been rotated past the edge of one of the thicknesses of metal between kerfs 26.

Figures 1 through 4 illustrate one type of mechanism which may be used to impart an oscillating movement to the cutter 17. A pair of crank arms 28, joined by a cross-head 29, are pivoted as at 30 to depending legs 31 which form a part of the motor mounting inside case 10. The lower end of each crank arm 28 is slotted as at 32 to receive a headed stud or rivet 33 at the end of a crank arm 34, one of which is disposed at each end of the cutter sleeve 17. A shaft 35 leading from the motor (not shown) has an offset portion 36 projecting through a slot 37 in a flange 38 of the cross-head 29. It will be seen that rotary movement of shaft 35 will be translated into oscillating movement of the cutter sleeve 17 by means of the mechanism just described. The range of oscillation is illustrated by Figures 6 and 7, and amounts to approximately 120 degrees.

In the dry shaver illustrated and described the closeness of the cut may be controlled by the operator. It is obvious that in using an oscillating type of cutter the shaver may be moved in two directions in its shaving operation. The closest shave will be obtained by holding the shaver normal to the skin surface and if the operator wishes to cut the hairs a little less closely to the skin surface, the shaver may be held at a slight angle to the normal position. This causes the shearing point to move slightly away from the skin surface, moving about some point on the lower end of curve 24 or the flat 25 as a fulcrum.

By virtue of the sharpness of the stationary cutting edges, hair may be sheared as close to the base as desired. It will be seen that each hair is sheared off on the opposite side of a very sharp, razor-thin edge. This edge could hardly be called a thickness of metal.

I claim:

1. A dry shaver comprising, in combination, a head consisting of complementary head portions each having a cutting edge, and a cutter having an oscillating movement within said head, said cutter being a split sleeve having two series of kerfs cut therein, the ends of the kerfs being substantially normal to the wall of the sleeve, said kerf ends forming cutting edges disposed on each side of the split and spaced therefrom, the two series of cutting edges on said cutter sleeve being respectively adapted to coact with the cutting edges in said head portions.

2. A dry shaver comprising, in combination, a head having a plurality of cutting edges and a cutter having an oscillating movement within said head, said cutter being a split sleeve and having two series of kerfs cut therein the ends of the kerfs being substantially normal to the wall of the sleeve, said kerf ends forming cutting edges disposed on each side of the split and spaced therefrom, the two series of cutting edges on said cutter sleeve being respectively positioned to coact with the cutting edges in said head.

3. A dry shaver comprising, in combination, a head having a plurality of cutting edges and a cutter having an oscillating movement within said head, said cutter being a split sleeve and having two series of kerfs cut therein the ends of the kerfs being substantially normal to the wall of the sleeve, said kerf ends forming cutting edges disposed on each side of the split and spaced therefrom, the two series of cutting edges on said cutter sleeve being respectively positioned to coact with the cutting edges in said head, said cutter sleeve having a yielding frictional engagement with said head.

4. A dry shaver comprising, in combination, a head consisting of complementary head portions each having a series of alternately positioned cutting edges and combing slots in one end thereof arranged with the combing slots in each head portion opposite the cutting edges in the other head portion and adapted to guide hairs thereto and an oscillating cutter within said head, said cutter being a split sleeve having a series of slotted cutting edges on each side of the split and spaced therefrom, one series of cutting edges in said cutter being adapted during one movement of the cutter to coact with the cutting edges in one of said head portions and the other series of cutting edges in said cutter being adapted during the reverse movement of said cutter to coact with the cutting edges in the other of said head portions.

5. A dry shaver comprising, in combination, a head consisting of complementary head portions each having a series of alternately positioned cutting edges and combing slots in one end thereof arranged with the combing slots in each head portion opposite the cutting edges in the other head portion and adapted to guide hairs thereto and an oscillating cutter within said head, said cutter being a split sleeve having a series of slotted cutting edges on each side of the split and spaced therefrom, one series of cutting edges in said cutter being adapted during one movement of the cutter to coact with the cutting edges in one of said head portions and the other series of cutting edges in said cutter being adapted during the reverse movement of said cutter to coact with the cutting edges in the other of said head portions, said cutter having a yielding frictional engagement within said head.
